UNITED STATES PATENT OFFICE.

FREDERICK QUINT, OF WILLOWS, CALIFORNIA.

LIFTING-JACK.

SPECIFICATION forming part of Letters Patent No. 366,792, dated July 19, 1887.

Application filed April 7, 1887. Serial No. 234,082. (No model.)

To all whom it may concern:

Be it known that I, FREDERICK QUINT, of Willows, Colusa county, State of California, have invented an Improvement in Lifting-Jacks; and I hereby declare the following to be a full, clear, and exact description of the same.

My invention relates to that class of lifting-jacks in which the power of the pivoted lever is transmitted through links to the vertically-movable lifting-head; and my invention consists in the combination and arrangement of the guide-standard, the pivoted lever, the lifting-bars, and the adjustable and vertically-movable lifting-head, as I shall hereinafter fully describe.

The object of my invention is to provide a simple and powerful lifting-jack adapted, by reason of its arrangement of lever, to be placed under a weight without interference from said lever, and by reason of its readily-adjustable lifting-head to be fitted for different heights.

Referring to the accompanying drawings for a more complete explanation of my invention, Figure 1 is a perspective view of my lifting-jack. Fig. 2 is a perspective detail of the lower portion. Fig. 3 is a section through the lifting-head E.

A is the guide-standard having a stable base, a.

B is a bent or angled lever having one end formed with or connected to a handle, b, of proper shape and of a length which carries it but little above the top of the standard when in a vertical position. The required length of the handle is gained by pivoting the lever B to the standard near its base, said pivot being through the shorter arm of the lever, as shown at C. The lever B is a slotted or forked one, passing on each side of the standard.

D are parallel lifting-bars, which pass up on each side of the standard, their lower ends being pivoted at d to the projecting ends of the lever B.

E is the lifting-head, having a stock, e, with a hole through it, the end walls of the hole being beveled, making it an inclined aperture, so as to cause the head to cramp on the bars when fitted upon them. The stock e has a short handle, e', extending backwardly from

it, for convenience in moving it up and down to adjust its initial position on the links.

In order to increase the hold or bite of the lifting-head on the bars, I secure strips of steel, F, to the surfaces of the stock e and allow the edges of these strips to come in contact with the bars. These steel strips will not be subject to much wear, and will preserve the best possible frictional contact.

The operation of my lifting-jack is as follows: By moving the lifting-head to a slight angle it may be readily moved up or down on the bars, to regulate approximately the proper height. The handle b is elevated to lie close to the standard, whereby the inner end of the lever B is depressed, the bars drawn down, and the lifting-head brought low enough to pass under the weight. When in proper position, the handle is forced down, thereby elevating the inner end of the lever and raising the bars, which carry the head up with them, thus lifting the weight, which of course cramps the head firmly on the bars. In this movement the parts are all guided vertically by the standard, to which they are held by the apertured stock of the lifting-head, which fits over both bars and standard.

The handle b, as before stated, has sufficient length to give the necessary power, and yet by pivoting its lever so low down the top of the handle is but little higher than the standard, and it will not therefore be in the way when the jack is placed under the weight preparatory to lifting it. This construction also gives facility in handling the jack, as the hand may grasp the tops of the standard, bars, and handle all at once.

Having thus described my invention, what I claim as new, and desire to secure by Letters Patent, is—

1. The combination, in a lifting-jack, of a guide-standard, a bent lever having a handle and being slotted and pivoted on the standard, lifting-bars passing up on each side of the standard and pivoted at their lower ends to the end of the bent lever, and a lifting-head fitted over the standard and lifting-bars and carried by the lifting-bars, substantially as herein described.

2. The combination, in a lifting-jack, of a

guide-standard, a bent lever having a handle and slotted and pivoted on the standard near its lower end, lifting-bars passing up on each side of the standard and pivoted at their lower ends to the end of the bent lever, and an adjustable lifting-head having a stock with an inclined or beveled walled aperture for fitting over the standard and lifting-bars and cramp-

ing on said bars under the weight, substantially as herein described.

In witness whereof I have hereunto set my hand.

FREDERICK QUINT.
